UNITED STATES PATENT OFFICE.

GEORGE A. BURNHAM, OF SAUGUS, MASSACHUSETTS, ASSIGNOR TO SEARS B. CONDIT,
OF BROOKLINE, MASSACHUSETTS.

ELECTRIC SWITCH.

Application filed October 12, 1920. Serial No. 416,504.

To all whom it may concern:

Be it known that I, GEORGE A. BURNHAM, a citizen of the United States, residing at Saugus, in the county of Essex and State 5 of Massachusetts, have invented an Improvement in Electric Switches, of which the following is a specification.

This invention relates to electric switches having movable means to absorb energy developed therein upon circuit interruption, as a resiliently supported oil receptacle adapted to be moved downward upon the development of abnormal gaseous pressure conditions within the switch resulting from 15 circuit interruption, as set forth in my Patent No. 1,413,156, dated April 18, 1922 and my co-pending application, Serial No. 374,276, filed April 16, 1920.

The object of the present invention is to 20 provide a switch of the type above set forth with means gradually to arrest the movement of the movable means, as the oil receptacle, after it has moved sufficiently to accomplish its purpose.

25 Briefly this object is attained by the provision of shock-absorbing means adapted to resist movement of the oil receptacle and gradually bring it to rest. The shock absorbing means may be of any desirable type, 30 as friction, hydraulic and the like, and a desirable means may comprise a resilient bumper connected with the switch frame and interposed in the path of movement of the oil to be engaged by it and gradually to arrest 35 its movement. Upon the reduction of pressure within the switch, the receptacle will be returned to its normal position through the influence of its resilient supporting means.

40 Fig. 1 is a side elevation of a switch of the type set forth in my Patent No. 1,413,156, dated April 18, 1922 embodying my present invention.

Fig. 2 is a side elevation, partly in section 45 of a switch of the type set forth in my co-pending application Serial No. 374,276, filed April 16, 1920, embodying my present invention.

Fig. 3 is a transverse vertical section of 50 the switch of Fig. 1.

Fig. 4 is a side elevation, partly in section, of the switch illustrated in Fig. 1, embodying a modified form of the invention.

Fig. 5 is a plan view of the bumper along line 5—5 of Fig. 4.

Fig. 6 is a transverse sectional elevation along line 6—6 of Fig. 4.

Fig. 7 is a further modified form of means for arresting the movement of the oil receptacle.

Fig. 8 is a plan view along line 8—8 of Fig. 6.

As here shown, the switch of the type set forth in my Patent No. 1,413,156, dated April 18, 1922, which I have chosen in Fig. 1 to illustrate my present invention, includes the switch frame 1 having the peripheral depending apron 2 within which the oil receptacle 3 is movably received. Said oil receptacle is contained within and supported by an outer or spill receptacle 4 whose side walls are spaced from the side walls of the oil receptacle and extend upwardly beyond the end of said apron 2.

Said oil receptacles rest upon and are supported by the grid 5 extended transversely beneath the receptacles and having end portions projecting therebeyond. Rods 6 are secured in the projecting portion of said grid and extend upward beyond opposite side walls of the spill receptacle and are slidably received in openings in the lugs 7 extended from the switch frame. The upper portions of said openings in the lugs are enlarged to form the recesses 8. Compression springs 9 are received in said recesses over the ends of said rods, which are screw-threaded. Nuts 10 are removably received on the threaded ends of said rods and engage the upper ends of said springs, whereby the oil receptacle is yieldingly supported in position with respect to the switch members 11 carried by the switch frame. The oil receptacle may be removed from position by removing said nuts 10.

The oil receptacle herein described comprises the movable member adapted to move to absorb energy developed within the switch resulting from circuit interruption.

While any desirable means may be employed for gradually arresting and governing the movement of the oil receptacle, for the purpose of illustrating my present invention I have, in Fig. 1, illustrated the shock-absorbing or movement-governing means for the oil receptacle as comprising the friction

device comprising the two friction arms 12 and 13 having enlarged cooperating frictional bearing portions 12^a and 13^a connected by the center bolt 14 and pressed into adjustable yielding frictional engagement by the spring washer 15 and nut 16 carried on the end of said bolt. The ends of said arms 12 and 13 are pivotally secured to the oil receptacle and a fixed support, as the switch frame, either directly or, as here shown, through the straps 17 and 18 secured respectively to the switch frame and the supporting grid 5 of the oil receptacle.

In Fig. 2, the shock-absorber arms 12 and 13 are pivotally secured to the oil receptacle 3 through the lug 19, and the platform 20 supporting the oil receptacle.

Preferably two shock-absorbing devices are employed, which are arranged on opposite sides of the oil receptacle to give a balanced action.

In both arrangements, the action is the same. The shock-absorbers serve to restrict the movements of the oil receptacle away from the switch frame and cause it to move less violently and also cause its return to normal position to be more gradual.

The shock-absorber may be arranged to govern the movement of the oil receptacle throughout its movements or they may be arranged to permit an unrestricted, or less restricted, movement of the receptacle for a certain extent of movement and thereafter a restricted or more restricted further movement.

In the modifications illustrated in Figs. 4 through 8, the oil receptacle, as the movable energy absorbing means, is permitted a certain amount of unrestricted movement and thereafter the movement is restricted and the receptacle is gradually brought to rest.

In the modifications illustrated in said figures, the energy or shock absorbing means comprises a resilient bumper including the flat U-shaped strap of steel or other suitable metal formed with the flat bottom portion 21 extended beneath the grid 5 supporting the oil receptacle, and the two arms 21^a extended upwardly beyond the side walls 50 of the spill receptacle midway between the receptacle supporting rods 6. Lugs 22 are formed on the switch frame midway between said lugs 7 and said arms of the strap are removably bolted thereto by the bolts 23. The bottom portion 21 of the strap is spaced a suitable distance below the bottom of said grid and resilient means, as the rubber block 24 of suitable characteristics, is secured thereto by the screws 25. The dimensions of said strap are such that normally said block is supported, say, half an inch below the bottom of the grid. When the oil receptacle is moved sufficiently downwardly by gaseous pressure conditions within the switch, it will attain considerable momen-

tum and when it strikes the resilient block, it will compress it and be brought gradually to rest.

To remove the oil receptacle said strap will first be removed.

In the modifications illustrated in Fig. 6, the rods 6 are fixed in the lugs 7 of the switch frame and slidably extended through openings in the receptacle supporting grid 5 and beyond said grid. The extended ends of said rods are threaded and plates 26 are removably secured thereon by the nuts 27 threaded on the extended ends of said rods. Compression springs 28 encircle said rods between said plates 26 and grid 5 and yielding support the oil receptacle in normal position about the switch members. A plurality of resilient rubber blocks 29 are secured to said plates 26 and said plates are spaced sufficiently below said grid to permit the desired extent of movement of the oil receptacle before making contact with said blocks. The shock-absorbing action is essentially the same as before.

The oil receptacle may be removed by first removing said plates 26.

It is obvious that other shock-absorbing means may be provided, and otherwise arranged without departing from the spirit of my invention.

I claim:

1. An electric switch having a component adapted to move to absorb energy, yielding supporting means for said component, and yielding means to control the action of said supporting means.

2. An electric switch having a component adapted to move to absorb energy, yielding supporting means for said component, and energy-absorbing means for said yielding supporting means.

3. An electric switch having an oil receptacle adapted to move downward to absorb energy and means to govern its downward movement and return it gradually in position.

4. An electric switch having a component adapted to be moved under conditions resulting from circuit interruption, yielding supporting means for said component, and means gradually to arrest the movement of said component.

5. An electric switch having a fixed component, a component adapted to be moved under conditions resulting from circuit interruption, a yielding connection between said fixed and movable components, and means extended between said fixed and movable components arranged gradually to arrest the movement of said movable component.

6. An electric switch having a fixed component, a second component having a yielding connection with said first component and movable under conditions resulting

from circuit interruption and means gradually to arrest the movement of said movable component.

7. An electric switch having a fixed component, a second component having a yielding connection with said first component and movable under conditions resulting from circuit interruption and means extended between said fixed and movable components gradually to arrest the movement of said movable component.

8. An electric switch having a fixed component, a second component movable under conditions resulting from circuit interruption to absorb energy, yielding means connecting said fixed and movable components and other yielding means to limit the extent of movement of said movable component gradually.

9. An electric switch comprising a switch frame, switch members carried thereby, an oil receptacle supported about said switch members movable under conditions resulting from circuit interruption, yielding supporting means for said oil receptacle and resilient means arranged gradually to arrest the movement of said receptacle.

10. An electric switch comprising a switch frame, switch members carried thereby, an oil receptacle yieldingly supported about said switch members movable under conditions resulting from circuit interruption and yielding means engageable with said receptacle after a predetermined extent of movement thereof, to restrict further movement thereof.

11. An electric switch comprising a switch frame, switch members carried thereby, an oil receptacle having means arranged yieldingly to support it about said switch members and means engageable with said receptacle after a predetermined extent of movement thereof, gradually to arrest the movement of said receptacle.

12. An electric switch comprising a switch frame, switch members carried thereby, an oil receptacle, means yieldingly connecting said receptacle with said switch frame admitting of its movement away from said frame under conditions resulting from circuit interruption, and yielding means arranged to be engaged by said oil receptacle to restrict further movement thereof.

13. An electric switch comprising a switch frame, switch members carried thereby, an oil receptacle, means yieldingly connecting said receptacle with said switch frame ad-

mitting of its movement away from said frame under conditions resulting from circuit interruption, and resilient means carried by said frame engageable by said oil receptacle gradually to restrict further movement thereof.

14. An electric switch comprising a switch frame, switch members carried thereby, an oil receptacle, means yieldingly connecting said receptacle with said switch frame admitting of its movement away from said frame under conditions resulting from circuit interruption, and a strap carried by said frame extended below the bottom of said receptacle having a resilient member engageable with said receptacle gradually to restrict its movement.

15. An electric switch comprising a switch frame, switch members carriers thereby, an oil receptacle, means yieldingly connecting said receptacle with said frame admitting of its movement away from said frame under conditions due to circuit interruption, a U-shaped strap carried by said frame surrounding said receptacle, and a resilient member carried by said strap engageable with the bottom of said receptacle gradually to restrict movement of said receptacle.

16. An electric switch comprising a switch frame, switch members carried thereby, an oil receptacle, means removably connecting said receptacle yieldingly with said frame admitting of its movement away therefrom under conditions resulting from circuit interruption, a U-shaped strap removably fixed to said frame and surrounding said receptacle, and a resilient member carried by said strap engageable with the bottom of said receptacle gradually to restrict movement of said receptacle.

17. An electric switch having a switch frame, an oil receptacle having means yieldingly connecting it with said frame, and shock-absorbing means extended between said frame and receptacle operable gradually to restrict movement of said receptacle.

18. An electric switch having a switch frame, an oil receptacle removably connected with said frame, yielding means included in said connection, and shock-absorbing means removably extended between said frame and receptacle operable gradually to restrict movement of said receptacle.

In testimony whereof, I have signed my name to this specification.

GEORGE A. BURNHAM.
